UNITED STATES PATENT OFFICE.

EDWARD M. STILES, OF MOUNT PLEASANT, IOWA, ASSIGNOR TO U. S. SLICING MACHINE COMPANY, OF LAFORTE, INDIANA, A CORPORATION OF INDIANA.

HOLDER FOR SLICING-MACHINES.

1,400,698.

Specification of Letters Patent. Patented Dec. 20, 1921.

Application filed July 2, 1918. Serial No. 243,022.

To all whom it may concern:

Be it known that I, EDWARD M. STILES, a citizen of the United States, residing at Mount Pleasant, in the county of Henry and State of Iowa, have invented certain new and useful Improvements in Holders for Slicing-Machines, of which the following is a specification.

The object of this invention is to provide a device of the class named which shall be of improved construction and operation.

The invention is exemplified in the combination and arrangement of parts shown in the accompanying drawings and described in the following specification, and it is more particularly pointed out in the appended claims.

In the drawings—

Figure 1 is a rear elevation of a work holder for a slicing machine embodying one form of the present invention.

Fig. 2 is a vertical sectional view on line 2—2 of Fig. 1.

Fig. 3 is a view similar to Fig. 1 showing a modification.

Fig. 4 is a vertical section on line 4—4 of Fig. 3; and

Fig. 5 is a fragmentary top plan of the holder shown in Fig. 3 with parts in section along line 5—5 of that figure.

In slicing machines of the usual form, there is provided a reciprocating table shown at 10 in the drawings, upon which a sliding work holder or meat plate 11 is mounted. The material to be sliced is placed on the plate 11 and held during the slicing operation by a clamp or holder of some form. It is usual to provide the edge of the table 10 which passes adjacent the slicing knife during the slicing operation with a corrugated plate 12 which supports the portion of the meat, or other material being sliced projecting toward the slicing knife. After a piece of material has been almost completely sliced, as shown at 14 in Fig. 2, it is impossible to longer clamp the material upon the meat plate 11 by a clamp which bears upon the upper face of the material, and the present invention provides means for engaging the face of the material opposite that from which the slices are being cut for the purpose of forcing the material downwardly upon the plate 12 so that its bottom surface may be firmly held against this plate, while at the same time

the rear surface is also grasped and held in position. The holder includes a frame having vertical side bars 15 and an upper cross-bar 16, the frame being held in position upon the meat plate 11 by hooks 17 and 18 arranged to engage uprights 19 and 20, respectively. The uprights 19 and 20 are carried by the guide bars 21 which form the sides of the support 11 and which slide upon the upper surface of the table 10. The space within the holder frame formed by the bars 15 and 16 is filled by an upright plate 22 having lugs 23 projecting from its rear face, the lugs being provided with inclined slots 24 which engage pins 25 extending inwardly from the inner faces of the bars 15. A pair of bearing lugs 26 is also secured to the rear face of the plate 22 to which lugs are pivoted links 27 having their opposite ends pivotally connected to a rod 28 journaled at its center in an opening passing through an operating handle 29. The handle 29 is fulcrumed upon a pin 30 connected to the upper cross-bar 16 by bearing brackets 31. On the front face of the plate 22 is a plurality of forwardly and downwardly inclined prongs or teeth 32 which engage the meat or other material to be sliced and hold it in place. In operating the holder, the meat or other material is placed against the points of the teeth 32 in the position shown by broken lines in Fig. 2 with the lower face of the meat held firmly against the upper surface of the plate 12, the plate 22 being retracted so that it occupies the position shown in full lines in Fig. 2. While the operator holds the meat in this position with one hand, he presses downwardly upon the handle 29 with the other hand, thus forcing the plate 22 with its teeth forwardly and downwardly guided, by the slots 24 and pins 25. This causes the teeth 32 to enter the rear face of the meat, and at the same time crowds the meat firmly against the supporting surface of the plate 12. The downward inclination of the teeth 32 prevents any upward, forward or lateral movement of the meat during the slicing operation, and the plate 12 supports the meat against downward movement. At the same time the corrugations in the upper surface of the plate 12 prevent lateral movement of the portion of the meat projecting in front of the holder toward the slicing knife. It is of great advantage to have the meat firmly held in position by the holder.

held against these corrugations rather than supported entirely by the plate 12, for the reason that the portion of the meat projecting forwardly from the holder is held 5 against the lateral pressure of the slicing knife by the corrugations in the plate upon which it rests.

In the modified form shown in Figs. 3, 4 and 5, the material is forced downwardly 10 into engagement with the corrugated plate 12 by a pivotal movement of the teeth instead of a movement of the plate on which the teeth are supported. In this form a front plate 33 is rigidly secured to the frame 15 bars 15 and 16, and this plate is provided with a plurality of slots 34 having lugs 35 extending rearwardly from the edges thereof, and pins or teeth 36 supported on pivots 37 between the lugs 35. Each pin 36 is provided 20 with a rearwardly projecting bifurcated portion 38 which engages a pin 39 carried between spaced upright bars 40 arranged to move vertically in the rear of the plate 33. The bars 40 are all connected by 25 cross-bars 41 and 42 which have their ends guided in slots formed on the inner faces of the upright frame members 15. A pair of links 43 is pivoted to lugs 44 connected with the cross-bar 41, and the upper ends 30 of the links 43 are connected with the prongs 45 of an operating lever 46 by pivot pins 47. The lever 46 is fulcrumed at 48 on lugs 49 carried by the upper cross-bar 16 of the holder frame. A handle 50 may be attached 35 to the bar 16 for lifting the holder. The lever 46 and lugs 49 are provided with shoulders 51 and 52 for limiting the downward movement of the lever 46. In operation the lever 46 is held in its upper position 40 so that the pins 36 extend horizontally. The meat to be sliced is then placed upon the upper surface of the corrugated plate 12 and forced toward the holder until the prongs 36 penetrate the meat sufficiently to 45 permit the rear face of the meat to engage the front face of the plate 33. The lever 46 is then swung downwardly in the position shown in broken lines in Fig. 4, which movement tilts the prongs 36 downwardly, 50 as indicated in that figure, and thus draws the meat tightly into engagement with the front face of the plate 33, and at the same time forces it firmly into contact with the upper corrugated surface of the plate 12. The lever 46 and links 43 are preferably so 55 related to one another that the lever will pass dead center just before it reaches the limit of its downward movement, and in this way the pins are locked in their downward position. A similar or other locking arrangement may be provided for the form 60 shown in Figs. 1 and 2, if desired.

I claim:—

1. In a slicing machine, a support having 65 a surface on which material to be sliced may

be positioned so that one face of said material will extend at substantially right angles to said support, and means for engaging said angularly arranged face of said material to hold said material against said 70 surface.

2. In a slicing machine, a carrier having a horizontally arranged supporting surface for material to be sliced, means for engaging an upright face of material supported upon 75 said carrier and mechanism for moving said engaging means toward said support for pressing said material against the supporting surface of said carrier.

3. In a slicing machine, a carrier having 80 a work-supporting surface arranged to support material thereon with one face of said material at an angle to said surface, a work holder movable over said surface and having means thereon for engaging said angularly 85 arranged face of said material, mechanism for actuating said engaging means and for pressing said material against said surface.

4. A slicing machine comprising a work carrier having an upper corrugated supporting surface, a work holder movable over said surface, means on said work holder for engaging an upwardly extending face of material supported on said carrier and mechanism for actuating said engaging means for 95 pressing said material against said corrugated carrier.

5. A slicing machine comprising a work carrier having a horizontally extending surface for supporting material to be sliced, a 100 work holder movable over said surface and having teeth thereon arranged to penetrate an upwardly extending face of material resting upon said carrier, and means for moving said teeth downwardly toward said 105 carrier to press the material engaged thereby against the upper surface of said carrier.

6. A work holder for slicing machines comprising an upright member, teeth having pointed ends directed forwardly from said 110 member for engaging material to be sliced, an abutment for preventing downward movement of material engaged by said teeth, and means for moving said teeth downwardly toward said abutment to cause said 115 teeth and abutment to hold said material during a slicing operation.

7. A holder for slicing machines comprising an upright member, teeth arranged to project from the front face of said member, 120 all of said teeth being inclined forwardly and downwardly, and means for moving said member downwardly to cause said teeth to penetrate material to be sliced and to hold said material during a slicing operation.

8. A work holder for slicing machines comprising an upright frame, teeth having pointed ends directed forwardly from said 125 frame, means for moving all of said teeth downwardly to cause said teeth to clamp 130

material to be sliced, and means for locking said teeth in their clamping position.

9. In a slicing machine, a work carrier having a horizontally extending work-supporting surface, an upright work-holding frame mounted on said carrier, teeth carried by said work-holding frame and having pointed ends directed forwardly, and means for moving all of said teeth downwardly 10 toward said work supporting surface into a work-holding position in which said teeth have their forward ends inclined forwardly and downwardly toward said supporting surface.
- 15 10. A work holder for slicing machines comprising an upright plate, a plurality of forwardly and downwardly inclined teeth carried by said plate, and means for shift-

ing said plate and teeth forwardly and downwardly to cause said teeth to engage 20 material to be sliced and to hold said material during a slicing operation.

11. A work holder for slicing machines comprising a frame, means for supporting said frame in an upright position, a plate 25 carried by said frame and movable thereon, forwardly and downwardly inclined teeth on said plate, means for moving said plate on said frame, and guides for causing said plate to move forwardly and downwardly 30 relative to said frame in the direction of the inclination of said teeth.

In testimony whereof I have signed my name to this specification on this 27th day of June, A. D. 1918.

EDWARD M. STILES.
